MEANS FOR CONTROLLING FLUID LEAKAGE THROUGH JOINTS AND BEARINGS.

1,426,416.

Specification of Letters Patent. Patented Aug. 22, 1922.

Application filed September 16, 1920. Serial No. 410,731.

To all whom it may concern:

Be it known that I, LOUIS E. SHAW, a citizen of the United States, and residing at East Orange, county of Essex, and State of New Jersey, have invented certain new and useful Improvements in Means for Controlling Fluid Leakage Through Joints and Bearings, of which the following is a complete specification illustrated in the accompanying drawings.

The particular novel features of my invention are more fully pointed out in the annexed claims.

My invention has the purpose of controlling unavoidable fluid leakage at points where movable joints or shafts pass through bearings or sleeves from spaces of higher fluid pressure to spaces of lower fluid pressure and where it is impractical to provide the ordinary kind of stuffing boxes.

Among the many cases and devices to which my invention may be applicable are particularly internal combustion engines of various types, as will be described presently.

For instance, it is well known that leakages occur in the guide sleeves of the valve stems of internal combustion engines by which outside air is able to pass along the valve stem into the intake pipe leading to the cylinders, thereby diluting the mixture and causing erratic running of the engine, especially at low speeds.

To prevent such leakage of undesirable fluid through joints or guide sleeves, I propose to connect a portion of the interior of the guide sleeve to the point of higher pressure of fluid desired, so that when a leakage at such joints occurs, this desired fluid will leak through the joint to the point of lower pressure instead of the undesired outside air. Thus, while fluid leakage, per se, is not prevented by these means, yet, the fluid contained in the engine space having lower pressure will not be diluted or otherwise affected by such leakage, since only fluid of the same quality enters through the leakage.

While my improvement is applicable to all kinds of joints or devices by which the flow of fluid is controlled, I have illustrated my invention only as applied to internal combustion engines of two principal types, to wit, stationary cylinder engines and rotary cylinder engines. Particularly in the latter type of engine where it is necessary to utilize a portion of the stationary crank shaft for

conducting the combustible mixture, it becomes essential to provide a joint free from leakage of outside air.

In the accompanying drawings, Figure 1 illustrates in longitudinal vertical section a portion of a stationary cylinder internal combustion engine; and

Figure 2 illustrates in longitudinal vertical section a portion of a rotary cylinder engine.

Referring to Figure 1, 1 is the engine cylinder in which the piston 2 operates in the conventional manner. 3 is the intake valve which passes through the cylinder casting in which for this purpose, a guide sleeve 4 is disposed. Guide sleeves for valve stems are old in the art and at the present day, most of the higher class internal combustion engines are provided with such sleeves which may be replaced when worn by the valve stems.

5, is the intake duct which leads to the intake valve and 6 represents in more or less diagrammatical form the carburetor or vaporizer which may be of any suitable type known in the art and which is attached by means of flange 7 to the intake duct 5. The throttle valve for controlling the mixture admitted to the engine is shown at 8.

As has already been indicated before, leakages occur between valve stem 9 and its sleeve 4 even if the sleeve has only been slightly worn, especially in cases where the throttle valve 8 is partially closed, in which instance, a pressure exists in intake pipe 5 considerably lower than atmospheric pressure and the pressure existing in the carburetor outside of throttle 8. The small amount of combustible mixture thus admitted by the throttle valve is thus considerably diluted by the leakage of air past the valve stem, which causes an erratic running of the engine at such slow speeds.

To overcome this defect, I provide midway between the ends of sleeve 4, an annular chamber 10 which completely surrounds the valve stem and from which a number of transverse holes 11 lead through the walls of sleeve 4. In the cylinder casting is provided a chamber 12 which runs in parallel to the intake duct 5. The sleeve portion, containing holes 11 is located within chamber 12 at one end thereof. The other end of chamber 12 terminates in intake pipe 13 at a point 14 outside of throttle 8. This terminal 14 is preferably located a suitable

distance above the bottom portion of intake pipe 13 in order to avoid liquid fuel which might collect in the lower portion of this pipe, due to the so-called "loading" of the engine, from accidentally entering chamber 12 which might occur if opening 14 were located at the bottom of the pipe.

Thus, in case the sleeve 4 has been worn by the valve stem so that outside air might tend to leak into the combustion chamber, this is prevented by the present arrangement, because in the present case, the suction of the engine will draw in through the leaky portions of the sleeve 4 combustible mixture from chamber 12 by way of holes 11 and annular chamber 10, this mixture being supplied from the carburetor intake pipe 13 through opening 14.

The manner in which my improvement may be applied to rotary cylinder engines is shown in Figure 2 where it may be arranged, for instance, as follows:

15 represents the stationary crank shaft with the crank pin 16, on which shaft the cylinder casing 17 revolves for instance, by means of ball bearing 18. Only a portion of one cylinder 19 is shown in the drawings. The intake conduit for this cylinder is shown at 20. It connects at 26 with the rotary casing 17 which at this point is provided with an inner annular chamber 21. The crank shaft 15 is hollow, as shown at 22 and the carburetor which is diagrammatically indicated at 23, is fixed to the outer end of the crank shaft in such manner that the combustible mixture produced by the carburetor may enter the boring 22 through an opening 24 provided in the cylindrical wall of shaft 15. A similar boring 25 is provided in the crank shaft wall at the point where it is surrounded by annular chamber 21 so that there is thus established a passage for the combustible mixture from the carburetor through opening or port 24, shaft boring 22, port 25, annular chamber 21, coupling 26, intake conduit 20, to the intake valve 27 and thence to cylinder 19. To suitably throttle the mixture when desired, a throttle tube 28 is provided inside of shaft boring 22, which snugly fits to the wall of the boring, but is permitted to be oscillated therein by means of throttle lever 29 attached to the outer end of tube 28 which protrudes beyond shaft 15 for that purpose. Tube 28 is closed at its outer end by means of plug 30. A port 31 registering with port 24 is provided in the wall of the tube 28, this port being of sufficient peripheral length so as to maintain full communication between the interior of tube 28 and the carburetor 23 throughout the entire angle through which throttle arm 29 may be rocked. Throttle tube 28 is provided with a second part 32 which registers with port 25 provided in crank shaft 15, this tube

port, however, being of sufficiently small peripheral length, so that when throttle lever 29 is operated, the communication between the interior of tube 28 and annular chamber 21 may gradually be closed.

Since the cylinder casing 17 rotates on shaft 15, it becomes necessary to provide a joint between portion 33 of the cylinder casing and the crank shaft 15 at the point where the annular portion 21 of the intake conduit is located, in order to prevent atmospheric air from entering the annular chamber at that point and from disturbing the quality of the gas mixture established by the carburetor. In this particular case, my novel means of preventing such leakage are arranged as follows:

Instead of permitting cylinder casing portion 33 to contact with shaft 15 on a running fit, this casing portion is made at this point of essentially larger inner diameter than the outside diameter of shaft 15 to permit the insertion of two rings 34, each of which is provided with an internal annular chamber 35 equivalent to annular chamber 10 in Figure 1, these rings having a running fit on shaft 15 and being connected together at their flange portions 36 by means of transverse bolts 37, of which only one is shown in the drawings. By this construction, these two rings 34 constitute a unit which is held against a shoulder 38 provided in chamber 21 of casing portion 33, a washer 39 of cork or other suitable material, being provided at this point to prevent leakage of air into chamber 21. The ring unit is pressed against shoulder 38 by means of a ring 40 which bears through a washer 41 similar to washer 39 against the flange of the other ring. Sufficient friction is established by these means to cause the rotating casing to take along the two rings 34 so that there will be no wear on washers 39 and 41, but at the same time casing portion 33 may float on rings 34 in case slight strains occur during the operation of the engine, or slight wear in ballbearings 18 occurs.

Referring now again to annular chambers 35 of rings 34, these chambers each are in line with a boring 43 in shaft 15 which correspond to the transverse holes 11 in Figure 1. In line with each of these holes 43 a port 44 is cut into the tubular throttle 28 of sufficient peripheral length to establish communication between the interior of tube 28 and annular chambers 35 at any angle to which the throttle lever 29 may be set. Thus, in case slight wear should have occurred between rings 34 and shaft 15 which otherwise might cause a leakage of outside air at this point into the annular chamber 21, the leakage in this case will occur from the interior of tubular throttle 28 carrying gas mixture of the desired

quality through the leaky joint into chamber 21, similarly to the manner in which the device described with reference to Figure 1 operates. In the arrangement according to Figure 2, leakage from the outside air as well as from the interior of the crank casing, into chamber 21 is prevented.

It is obvious that the means by which I control such undesired fluid leakages may be employed as well in case of supplying liquids through joints or bearings of similar character where it is desired to prevent outside air or other fluid from entering through leaks which may occur in the joints.

I claim:—

1. Means for preventing in internal combustion engines, air leakage through joints into space carrying combustible mixture of pressure lower than atmospheric, comprising a tubular member extending from the outside into the low pressure mixture space, an element disposed within the tubular member and forming the joint therewith to be protected from leakage, said tubular member having an annular space midway between its ends which surrounds said inner element, means for producing combustible mixture at or near atmospheric pressure and means for connecting said annular space with said source of combustible mixture.
2. In a rotary cylinder engine a fixed hollow crank shaft having ports leading from its interior to the outside, a cylinder casing rotating thereon and means for supplying combustible mixture through said hollow shaft and said ports to the cylinder casing portion immediately surrounding the crank shaft, of a pair of spaced rings coupled together and rotatably fitted on said shaft and disposed between the latter and said surrounding casing portion and having one of said shaft ports located between them, each of said rings being rotatable with said casing and having an annular recess in the bearing surface adjacent to the shaft, said shaft having an auxiliary port for each of said recesses adapted to permanently communicate therewith, said surrounding casing portion having an annular chamber located in alignment with the space between said rings and with the shaft port adjacent to the rings to permit combustible mixture supplied to said hollow shaft to pass into the surrounding rotating cylinder casing portion, packing means for securing a gas tight joint between said rings and said surrounding cylinder casing and a tubular throttle in the interior of said shaft for controlling the gas mixture supply from said shaft ports to said cylinder casing portion.

LOUIS E. SHAW.
